PORTABLE TYPEWRITER CARRYING CASE

Eugene E. Mogensen, Bayside, N. Y.

Application July 13, 1948, Serial No. 38,524

6 Claims. (Cl. 45—68.2)

1

This invention relates to a carrying case for portable typewriters.

One of the objects of this invention is to provide a carrying case which is simple, practical and thoroughly durable. Another object is to provide a case of the above character which may be manufactured from inexpensive materials without undue labor costs. Another object is to provide a case of the above character which will be sturdy and well able to withstand continuous hard usage. Another object is to provide a case of the above character which is universal in that it may be used for all types of portable typewriters. Another object is to provide a case of the above character to which a portable typewriter may be easily and quickly connected or detached. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

Referring now to the drawings, in which is shown one of the various possible embodiments of the above invention,

Figure 1 is a perspective view of the carrying case, the cover in open position, certain parts of the cover being broken away for purpose of illustration;

Figure 2 is a horizontal section of the mechanism for connecting a typewriter to the case taken on the line 2—2 of Figure 4, certain parts of the case being broken away;

Figure 3 is a view similar to Figure 2 with certain parts in different relative positions and taken on the line 3—3 of Figure 5;

Figure 4 is a vertical section on an enlarged scale taken on the line 4—4 of Figure 2;

Figure 5 is a vertical section on an enlarged scale taken on the line 5—5 of Figure 3;

Figure 6 is a perspective view on an enlarged scale of certain of the parts mounted on the forward wall of the base of the case;

Figure 7 is a vertical section on an enlarged scale taken on the line 7—7 of Figure 5;

Figure 8 is a top plan of certain portions of the locking mechanism mounted on the front wall of the base of the case;

Figure 9 is a vertical section on an enlarged scale taken on the line 9—9 of Figure 3;

Figure 10 is a vertical section on an enlarged scale taken on the line 10—10 of Figure 3; and

Figure 11 is a vertical section on an enlarged scale taken on the line 11—11 of Figure 5.

Similar reference characters refer to similar parts throughout the several views of the drawings.

This typewriter case is of a universal type

2

which may be used with any make of portable typewriter and is provided with mechanism to securely connect any typewriter to the case after making one simple adjustment in the connecting mechanism, as will be pointed out hereinafter. In general, the metal connecting mechanism includes a clamping plate, generally indicated at 12, which may be moved toward and from the front wall 14 of the base 10 of the case by moving lever 16 downwardly and upwardly. Plate 12 is parallel to the rear of the typewriter framework and is so adjusted with respect to the back of a typewriter that when lever 16 is moved downwardly into locked position, as shown in Figure 5, the typewriter is clamped between clamping plate 12 (Figure 1) and the rear surface of plate 58. Lever 16 is provided with a tongue 16a which engages the framework on the front of the typewriter and holds it down in engagement with base 10, all as will be fully described hereinafter.

In detail, referring to Figure 1, the case includes base 10 and a cover, generally indicated at 18. The side walls of the base 10 are low to permit a typewriter to be used while it is mounted on the base. Cover 18 has side walls 20 of sufficient depth to accommodate the height of any portable typewriter and is preferably detachably connected to base 10 by detachable hinges (not shown).

All of the mechanism for connecting a typewriter to the case is mounted upon base 10. Clamping plate 12 is parallel to and is mounted for movement toward and from front wall 14. This plate includes a forwardly-extending portion 12a (Figure 2) having a longitudinal slot 22 therein. Portion 12a of clamping plate 12 is adjustably connected to a link 24 which also has a longitudinal slot 26 therein. The forward end of link 24 extends through a raised portion 28a of a bracket, generally indicated at 30. Bracket 30 is connected to the bottom 32 of base 10 by means of rivets 34 and 36. Longitudinal slots 26 and 22 are aligned with respect to each other and are utilized in mounting link 24 and portion 12a on a guide 38 (Figures 9 and 10), which includes a portion 38a extending upwardly through slots 22 and 26. Guide 38 is connected to the bottom 32 of base 10 by means of a rivet, generally indicated at 40 (Figure 9), the head 40a of which extends over link 24. Thus, guide 38 and bracket 30 serve to guide link 24 and portion 12a of clamping plate 12 as they are moved toward and from the front wall 14 of base 10.

Slots 22 and 26 also permit clamping plate 12 to be adjusted toward and from front wall 14 to accommodate typewriters of different sizes. To lock link 24 to portion 12a after an adjustment is made, the under surface of link 24 has transverse teeth 42 (Figure 10) formed thereon which engage transverse teeth 44 on the forward end of

portion 12a of clamping plate 12. A screw 46 passing through slot 26 and threading into portion 12a (Figure 2) acts through its head to clamp link 24 to portion 12a and thus hold teeth 42 in engagement with teeth 44. When it is desired to adjust link 24 with respect to clamping plate 12, screw 12a is loosened, teeth 42 and 44 become disengaged, and at this time clamping plate 12 may be moved toward or from link 24. When clamping plate 12 is properly positioned, screw 46 is tightened, and from then on, clamping plate 12 moves as though it were an integral portion of link 24.

Movement of clamping plate 12 toward and from front wall 14 is controlled by lever 16 (Figures 1, 4 and 5). Lever 16 is operatively connected to an actuating member, generally indicated at 50 (Figures 2, 3 and 6). Actuating member 50 includes a cam portion 50d which acts upon the forward end of link 24 to move link 24 rearwardly and includes a raised cam portion 50e which acts through lever 52 to move link 24 forwardly. Lever 52 is pivotally connected to bracket 30 by means of a pivot pin 54 and is pivotally connected to the forward end of link 24 by means of a pivot pin 56.

Actuating member 50 and handle 16 are mounted on the case by a supporting plate, generally indicated at 58 (Figures 2 and 4), which is connected to forward wall 14 of base 10 by means of rivets 60 and 62. The body of plate 58 is spaced from and parallel to wall 14 to form an enclosed space 60 within which actuating member 50 is mounted. Actuating member 58 is split along its center portion (Figure 6) to form a section 58a which abuts against plate 53 (Figure 2) and a section 58b which abuts against the rear surface of wall 14. The end portion 58c of member 50 extends rearwardly and abuts against the forward surface of supporting plate 58. Sections 58a and 58b and end portion 58c act as guides to insure movement of member 50 in a vertical plane as it moves longitudinally of plate 58. Member 50 rests upon bottom 32 and is held in position by lugs 64 and 66 stamped out of and extending forwardly from plate 58 (Figures 2 and 4).

The other end portion 50d of member 50 is angularly positioned with respect to wall 14 to form a cam surface so that when member 50 is moved upwardly, as viewed in Figure 2, it engages a lug 24a extending upwardly from the forward end of link 24 and moves link 24, and thus plate 12, away from wall 14, as viewed in Figure 2. Member 50 also includes an angularly-shaped portion 50e which forms a cam surface 68 engaging the angularly-shaped forward end 52a of lever 52. Thus, whenever member 50 is moved downwardly, as viewed in Figure 2, lever 52 is turned in a counterclockwise direction about pivot 54 and acts through its pivotal connection 56 to link 24 to move clamping plate 12 toward wall 14.

Lever 16, which moves member 50 transversely of the case, is pivotally connected to plate 58 by headed pivot pin 70 (Figures 2 and 7). A pin 74, mounted on member 50 extends into a cam slot 72 (Figures 4, 6 and 7) cut in the lower end of lever 16. Cam slot 72 is so shaped that when lever 16 is moved downwardly from the position it occupies in Figure 4 to the position it occupies in Figure 5, the slot acts upon pin 74 to move actuating member 50 to the left. Furthermore, when lever 16 is moved from the position it occupies in Figure 5 to the position it occupies in

Figure 4, cam slot 72 acts upon pin 74 to move member 50 to the right, as viewed in Figure 4.

As pointed out hereinabove, tongue 16a of lever 16 prevents the front end of the typewriter from moving upwardly with respect to base 10 when the typewriter is locked to base 10. To accomplish this, tongue 16a is pressed downwardly into engagement with the upper surface of the forward portion of the frame of a typewriter diagrammatically indicated by the dotted lines 88 (Figure 11). To hold lever 16 in a locked position, it is provided with a detent 82 (Figures 7 and 11) which coacts with teeth 84 formed on and extending forwardly from one edge of a recess 86 formed in plate 58 (Figures 4 and 11). Lever 16 is so shaped that detent 82 is normally resiliently pressed into engagement with teeth 84. Thus, whenever lever 16 is pressed downwardly, detent 82 ratchets over teeth 84 until tongue 16a engages the framework of the typewriter.

As lever 16 is being moved into engagement with the framework of the typewriter, clamping plate 12 is being moved forwardly to clamp the typewriter against the forward surface of plate 58. To improve the frictional grip of plate 12 upon the rear surface of the typewriter, it is preferably provided with a rubber pad 90 secured to plate 12 in any suitable manner.

In operation, screw 46 is loosened (Figures 1 and 2), and the portable typewriter to be mounted on the case is placed on bottom 32 with its forward end in engagement with plate 58. Plate 12 is then moved forwardly until pad 90 is spaced a slight distance from the rear surface of the typewriter's framework. The typewriter is then removed and screw 46 tightened. At the time this adjustment is made, handle 16 is in a raised position, as shown in Figures 1 and 4.

Next, the typewriter is placed in the case with its forward end abutting against plate 58 (Figure 1) and handle 16 is pressed downwardly until portion 16a engages the upper surface of the front portion of the framework 80 of the typewriter (Figure 11). During the downward movement of lever 16, plate 12 is moved forwardly so that it engages the rear surface of the typewriter and presses it tightly against plate 58. Because of pad 90, the rear portion of the typewriter is securely connected to base 10, and the forward portion of the typewriter is held in position by tongue 16a of lever 16. When it is desired to remove the typewriter from the case, the user presses forwardly on fingerpiece 16b (Figures 7 and 11) to disengage detent 82 from teeth 84.

Lever 16 may then be raised from the position it occupies in Figure 5 to the position it occupies in Figure 4. This moves plate 12 rearwardly, freeing the typewriter so that it may be removed from the case.

It will thus become clear that plate 12 may be adjusted to suit any typewriter, no matter what its length, and lever 16 is also so constructed that it will engage the top surface of the forward portion of the framework of all portable typewriters and can be locked in that position. In this connection, it might be noted that cam slot 72 (Figure 4) is so shaped that plate 12 (Figure 2) is in typewriter holding position by the time detent 82 reaches the uppermost tooth of teeth 84. Thus, regardless of the height of the front of a typewriter, the typewriter will be just as securely mounted when the detent engages the uppermost tooth as when it engages the bottom tooth.

It will thus be seen that a thoroughly practi-

cal and efficient typewriter case has been disclosed which is adjustable to carry portable typewriters of all makes. Furthermore, the connecting mechanism is such that it may be readily and quickly operated to mount a typewriter on or detach it from the case. Accordingly, it will be seen that the several objects hereinabove mentioned, as well as many others, have been successfully accomplished.

As many possible embodiments may be made of the above invention, and as many changes might be made in the embodiment above set forth, it is to be understood that all matter hereinabove set forth or shown in the accompanying drawings is to be interpreted as illustrative and not in a limiting sense.

What is claimed is:

1. In a portable typewriter carrying case including a base and a cover, said base including a front wall, in combination a clamping member, means mounting said clamping member on said base for movement toward and from the front wall of said base, a lever mounted on said front wall, means connecting said lever and said clamping member, said lever actuating said clamping member when moved downwardly to move said clamping member forwardly to clamp a typewriter between said wall and said clamping member, means formed on said lever for securing the front portion of the typewriter to the case when said lever is moved downwardly, and means for locking said lever in a down position with said last-mentioned means in engagement with the front portion of said typewriter whereby the front portion of said typewriter is connected to said case by said lever.

2. In a portable typewriter carrying case including a base and a cover, said base including a front wall, in combination, a clamping member, means mounting said clamping member on said base for movement toward and from the front wall of said base, a lever mounted on said base, means connecting said lever and said clamping member, said lever actuating said clamping member when moved downwardly to move said clamping member forwardly to clamp a typewriter between said wall and said clamping member, said first-mentioned means being manually adjustable to permit the distance between said clamping member and said front wall to be varied independently of the moving of said clamping member by said lever, and a member associated with said lever when said lever is in a down position for connecting the forward portion of said typewriter to said base.

3. In a portable typewriter carrying case including a base and a cover, said base including a front wall, in combination, a clamping member mounted on said base, a lever, an actuating member, said lever being connected to said actuating member and being adapted to move said actuating member longitudinally of said front wall, means connecting said actuating member and said clamping member, said clamping member moving toward and from said front wall as said actuating member is moved by said lever and being adapted to clamp said typewriter against said front wall, and means associated with said lever for connecting the front portion of said typewriter to said base when said typewriter is clamped against said front wall.

4. In a portable typewriter carrying case including a cover and a base, said base including a

front wall, in combination, a clamping member spaced from and positioned substantially parallel to said front wall, said clamping member including a portion extending toward said front wall along the bottom of said base, adjustable means in said portion to permit said clamping member to be adjusted toward and from said front wall, a lever mounted on said front wall and moving longitudinally of said front wall, an actuating

10 member moving longitudinally of said front wall, means operatively connecting said actuating member and the forward section of the forwardly-extending portion of said clamping member, said lever upon being actuated acting through 15 said actuating member and said last-mentioned means to move said clamping member forwardly to clamp a typewriter against said front wall, said lever moving downwardly toward said bottom when it is actuated to move said clamping member toward said front wall, means to hold said lever in locked position when a typewriter is clamped between said clamping member and said front wall, and means on said lever engaging the front of said typewriter for securing said typewriter to said base when said lever is in locked position.

5. In a portable typewriter carrying case including a base and a cover, said base including a front wall, in combination, a clamping member 30 mounted on said base, a lever, an actuating member, said lever being connected to said actuating member and being adapted to move said actuating member longitudinally of said front wall, cam means on said actuating member operatively 35 associated with said clamping member, said cam means moving said clamping member toward said front wall as said actuating member is moved by said lever and being adapted to clamp said typewriter against said front wall, and means associated 40 with said lever for connecting the front portion of said typewriter to said base when said typewriter is clamped against said front wall.

6. In a portable typewriter carrying case including a base and a cover, said base including a front wall, in combination, a clamping member mounted on said base, a lever, an actuating member, said lever being connected to said actuating member and being adapted to move said actuating member longitudinally of said front wall, a second 45 lever pivotally connected to said clamping member, cam means on said actuating member operatively associated with said second lever, said cam means acting through said second lever to move said clamping member into clamping position 50 with respect to said typewriter when said first-mentioned lever is moved downwardly, and means associated with said first-mentioned lever for connecting the front portion of said typewriter to said base when said typewriter is clamped against 55 said front wall.

EUGENE E. MOGENSEN.
